FENCE WIRE FASTENER

Filed June 5, 1933

INVENTOR

John A. Moritz
By
Charles A. Lantz

ATTY

To apply the eye 6 over the strand wire, a nail 7, see dotted lines in Fig. 2, or an equivalent article, is inserted through the eye 6 and with a sweep of the nail about the strand wire, the eye 5 is caused to be bent over the strand wire frictionally gripping the same between the body of the fastener and against the face of the post. Such action deforms the eye slightly, or causes it to be spread, but its extremity, as shown, will be 10 caused to lie closely adjacent the strand wire leaving no jagged or projecting end.

While I have described the fastener as being applied to the under side of the strand wire, it is obvious that it could be applied to the upper 15 side thereof.

What I claim is:—

1. A fence wire fastener composed of a wire member shaped to embrace a fence post, one end of the wire member being bent to lie over and 20 parallel to the adjacent part of the wire member to form a substantially J-shaped hook having its extremity free and spaced from said adjacent part of the wire member, whereby to enable the hook to be engaged over the fence wire, the opposite end of the wire member being bent outwardly to form an eye of substantially circular 25 form to receive a bending instrument, the eye having a free extremity which extends inwardly

of the eye, said eye being bodily bendable about the wire member whereby to enable same to be engaged over the fence wire and with its free extremity disposed opposite and in juxtaposition to the fence wire and between the inner side of 80 the eye and the adjacent part of said opposite end of the wire member, whereby said inner side of the eye, said adjacent part of the wire member and the fence wire protect the said free extremity of the eye.

2. A fence wire fastener composed of a wire member shaped to embrace a fence post, one end of the wire member being bent to form a hook to receive the fence wire, the opposite end of the wire member being bent outwardly and inwardly 90 to form an eye to receive a bending instrument, the eye having a free extremity which extends inwardly of the eye, said eye being bodily bendable about the wire member whereby to enable same to be engaged over the fence wire and with its free extremity disposed opposite and in juxtaposition to the fence wire and between the inner side of the eye and the adjacent part of said opposite end of the wire member, whereby said inner side of the eye, said adjacent part of the wire member and the fence wire protect the said free 95 extremity of the eye.

JOHN A. MORITZ.
